UNITED STATES PATENT OFFICE.

GEORGE H. FORSYTH, OF CHICAGO, ILLINOIS, ASSIGNOR TO MOTOR WHEEL CORPORATION, OF LANSING, MICHIGAN, A CORPORATION OF MICHIGAN.

DISK WHEEL.

Original application filed March 3, 1922, Serial No. 540,678. Divided and this application filed January 16, 1925. Serial No. 2,792.

My invention has to do with disk wheels and has for its principal object the provision of a wheel of the disk type wherein a composite disk of metallic and non-metallic layers is rendered susceptible of employment instead of the usual sheet steel disk, without impairment of strength under dead load, resistance to deforming stresses in road use, and life and efficiency under weather conditions and attack of the elements; all accompanied by a reduced cost of production, the elimination of noises due to resonance and an enhanced adaptability both to heavy commercial and light pleasure cars. I accomplish this object by the employment of a laminated disk of steel and a material having a substantially lower coefficient of elasticity than sheet steel, with or without the reinforcing inlay of steel interlocked with the other material and I may shape the disk and so assemble the same with the hub and rim as to place and maintain the disk under radially reacting stress, whereby to strengthen and reinforce the same against deformation by strains of use acting in the plane of the wheel or laterally thereof.

In order that the invention and its use may be readily understood by those skilled in the art I have set forth two embodiments of the same in the accompanying drawing and in the following detailed description predicated thereon. It will be understood that the principles of the invention are adaptable to other varied embodiments without sacrifice of their material advantages, wherefore the drawing and description are not to be taken in an unnecessarily limiting sense but as rather illustrative of the invention.

40 In the drawing,

Figs. 1 and 2 represent in radial section, fragmentary portions of disk wheels embodying the invention.

45 In Fig. 1 the fibrous sheets 11 forming the disk are assembled with a metallic reinforcing inlay 12, such as sheet steel, and prefer-

ably secured thereto in any suitable manner, although they may be independent of each other and shaped in the process of forming so as to lie in intimate contact throughout 50 their extent.

In Fig. 2 the disk is shown as comprising multiple sheets 13 of hardened originally plastic organic fiber such as wood pulp having imbedded therein an inlay sheet 14 of steel which is advantageously foraminous, being provided at spaced intervals with holes 15 by means of which the steel inlay and the fibrous sheets 13 are interlocked. It will be understood that there may be any desired 55 number of successive layers of metallic and non-metallic sheets constituting the disk.

It will be understood that the sheet materials employed as component parts of the disk, other than the inlays 12 of Fig. 1 and 14 of Fig. 2, have a decidedly lower coefficient of elasticity than has steel such as has been heretofore employed in the making of disk wheels, and such materials also possess in a less degree the property of resistance to deformation. I have found that while such materials are ordinarily not adapted alone to withstand the strains to which automobile wheels are subjected, yet when assembled with and reinforced by the steel inlay the 60 65 70 elasticity and resistance of such materials are so highly augmented that the wheel as a whole has a strength far more than sufficient to meet all requirements.

In assembling the disk with the hub and rim portions the intermediate portion of the disk may be advantageously maintained under radial stress by force applied at the hub 16, at the rim 19, or both, as set forth in detail in the parent application.

80 In the figures of the drawing, the means of assembling the rim 19 with the peripheral portion of the disk acts through force laterally applied and reacting inwardly in a direction toward the hub to stress not only 85 90 the intermediate portion of the disk but also the peripheral portion 20 thereof. Whether

this deforming force is applied at the hub by the bolts 17, or at the periphery, by the bolts 23 and 26, or both, the disk throughout its area is subjected to and maintained under 5 radial stress and its force of resistance to and recovery from strains is greatly enhanced.

As a means of assembling the disk with the rim and stressing the same by inward 10 radial reaction various expedients may be employed as for instance:

In Fig. 1 the laterally deflected peripheral portion of the disk underlies the felly member 21 by means of which it is held under 15 permanent stress, the rim 19 being assembled therewith by means of the clip 22 and the bolts 23.

Fig. 2 represents a construction in which the peripheral portion 20 of the disk is laterally disposed at a slight incline to the horizontal and the stressing of the disk is accomplished by the wedging action of the rim surface 24 under the force applied to the rim flange 25 by the bolts 26.

While in each of the figures I have shown an assembly which places and maintains the disk under stress, it will be understood that for some purposes this supplemental strengthening of the disk would not be required and the invention is not to be considered as necessarily an association of the two ideas of disk construction and wheel assembly, as the one has elements of decided value independent of the other.

I claim:

1. In a wheel, the combination with the hub portion and the tire-carrying peripheral portion, of an intermediate disk portion comprising metallic and non-metallic sheets, 40 the latter forming the exterior surface.

2. In a wheel, the combination with the hub portion and the tire-carrying peripheral portion, of an intermediate disk portion comprising metallic and non-metallic sheets 45 in contact substantially throughout the disk area, the latter forming the exterior surface.

3. In a wheel, the combination with the hub portion and the tire-carrying peripheral portion, of an intermediate disk portion comprising metallic and non-metallic sheets 50 in contact substantially throughout the disk area, the said disk assembled in the wheel under radially reacting stress.

4. In a wheel, the combination with the hub portion and the tire-carrying peripheral portion, of an intermediate disk portion comprising metallic and fibrous sheets in 55 contact substantially throughout the disk area, the said disk assembled in the wheel under radially reacting stress.

5. In a wheel, the combination with the hub portion and the tire-carrying peripheral portion, of an intermediate disk portion comprising steel and fibrous sheets in 60 contact substantially throughout the disk area,

the said disk assembled in the wheel under radially reacting stress.

6. In a wheel, the combination with the hub portion and the tire-carrying peripheral portion, of an intermediate disk portion comprising a plurality of sheets having different coefficients of elasticity, the sheet 70 having a lower coefficient forming the exterior surface.

7. In a wheel, the combination with the hub portion and the tire-carrying peripheral portion, of an intermediate disk portion comprising a plurality of sheets having different coefficients of elasticity and in contact substantially throughout the disk area, 80 the sheet having a lower coefficient forming the exterior surface.

8. In a wheel, the combination with the hub portion and the tire-carrying peripheral portion, of an intermediate disk portion comprising a plurality of sheets having different coefficients of elasticity mechanically interlocked and in contact substantially 85 throughout the disk area.

9. In a wheel, the combination with the hub portion and the tire-carrying peripheral portion, of an intermediate disk portion comprising a plurality of sheets of organic material and a sheet of steel secured thereto, the sheets in contact substantially 90 throughout the disk area.

10. In a wheel, the combination with the hub portion and the tire-carrying peripheral portion, of an intermediate disk portion comprising a plurality of sheets of non-metallic material and an inlay sheet of steel interposed therebetween, the sheets in 100 engaging contact substantially throughout the disk area.

11. In a wheel, the combination with the hub portion and the tire-carrying peripheral portion, of an intermediate disk portion comprising a plurality of sheets of non-metallic material and an inlay sheet of steel interposed therebetween, the sheets in engaging contact substantially throughout the 110 disk area, the said composite disk yieldable radially and assembled with the hub and rim portions of the wheel under radially reacting stress.

12. In a wheel, the combination with the hub portion and the tire-carrying peripheral portion, of an intermediate disk portion comprising a plurality of sheets of hardened originally plastic material and a foraminous 115 inlay sheet of steel interlocked therewith.

13. In a wheel, the combination with the hub portion and the tire-carrying peripheral portion, of an intermediate disk portion comprising a plurality of sheets of hardened originally plastic material and a foraminous inlay sheet of steel interlocked therewith, the said disk assembled in the wheel under radially reacting stress.

14. In a wheel, the combination with the 120

hub portion and the tire-carrying peripheral portion, of an intermediate disk portion comprising metallic and non-metallic sheets, the disk maintained under radially reacting stress.

15. In a wheel, the combination with the hub portion and the tire-carrying peripheral portion, of an intermediate disk portion comprising a plurality of mechanically in-

terlocked sheets having different coefficients 10 of elasticity.

16. In a wheel, the combination with the hub portion and the tire-carrying portion, of a composite body portion including a fo-
15 raminous metal disk.

In testimony whereof I have hereunto signed my name.

GEORGE H. FORSYTH.
